UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,157,810.

Specification of Letters Patent. Patented Oct. 19, 1915.

Application filed April 8, 1912. Serial No. 689,290.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming a part of this specification.

My invention relates to electric switches.

It has among its objects to provide an improved snap switch of a simple, durable and efficient character.

15 A further object of my invention is to provide a switch of this character which will be particularly adapted to flush switches.

Other objects and advantages of my improved construction will hereinafter appear.

I have illustrated my invention as applied to an electric flush switch. It is not however limited to use with this type of switch or to the precise construction herein 25 shown.

Figure 1 shows a side elevation of the switch in open circuit position. Fig. 2 shows a side elevation of the switch in closed circuit position. Fig. 3 shows a bottom plan view of the switch. Fig. 4 shows a sectional view on line 4—4 of Fig. 3. Fig. 5 shows a detail view of a part of the operating mechanism.

The switch mechanism includes a plurality of push button operated racks 1, a pinion 2 actuated thereby, movable contacts 3 adapted to engage stationary contacts 4 and operative connections between the pinion and the movable contacts including a 35 cam and resilient means for insuring a snap action.

The racks 1 reciprocate in a frame 5 and are provided with stops 6 to limit their downward movement in the same. As one 45 push-button is lowered the other is raised through the meshing of the teeth of the racks with the pinion. This pinion is mounted on a sleeve 7 which turns on a transverse shaft 8 journaled in depending 50 arms 9 carried by the frame. At a point beyond its periphery this pinion carries a ball holder 10 seated in the free ends of parallel members 11. This ball holder is preferably cylindrical, as shown in Fig. 5, and 55 houses a coiled spring 12 which normally

tends to throw balls 13 in the ends of the ball holder to their out position.

Cams 14 are fixed to the shaft 8 on opposite sides of the pinion 2 in such a position that their active surfaces are engaged by the balls 13. In a preferred form the cams are disk-shaped and identical, being provided with inturned flanges providing cam surfaces of the same conformation, and of substantially equal length and slope on the opposite sides of peaks 15. In order that the ball holder when turned by the movement of the pinion and push buttons may freely pass the peaks of the cams the ball holder is preferably slotted on each end as 60 at 16. The limits of travel of the ball holder and racks are established by projections 17 at the bottom of the slopes of the cams and the stops 6 on the racks. The limit of travel of the cams is established by providing each 65 of the disk-shaped cams with a cutaway portion 18, and slightly thickening the walls of the cams as at 19 at points adjacent these cutaway portions so that when the cam is oscillated this thickened portion will abut 70 against the edge of the depending frame 9 within which the shaft 8 is journaled.

The movable contacts 3 are fixed to the shaft 8 and insulated therefrom as by suitable insulation 20. These movable contacts move with the cams 14 with a quick snap action to make or break the circuit connections at the stationary contacts 4. In a preferred form the movable contacts 3 are arc-shaped, as shown in Figs. 1 and 2, and the 75 stationary contacts are resilient and arc-shaped so that a wiping action is produced which tends to keep the contacts clean. The stationary contacts 4 are preferably mounted on suitable supports 21 depending from the frame 5 and are provided with suitable terminal connections 22 in the form of binding posts; the contacts being insulated from the supports 21 by suitable insulation 23.

Assuming the switch to be in the position shown in Fig. 1 wherein the circuit is open and the left-hand push button is depressed, the operation of the switch is as follows: When the right-hand push-button is depressed the pinion 2 is turned toward the right. The ball holder 10 is carried with the pinion and the balls 13 engage the active surfaces of the cams 14, traveling up these active surfaces and being forced inward to 105 110

compress the spring 12 until they reach the peaks 15 of the cams. Until this point is reached no movement of the cams takes place. However, at the moment the balls 5 pass the crests of the cams the spring 12 is released, forcing the balls outward and throwing the cams 14 to the right in an opposite direction to the direction of movement of the ball holder. It is thus seen 10 that the balls move rapidly down the opposite slope of the cam and the cams are impelled in an opposite direction to the direction of movement of the balls with a quick snap action. Since the movable contacts 3 move with the cams 14 the circuit is therefore made at the contacts 4 with a quick snap action, the parts occupying the position shown in Fig. 2. Obviously, when it is desired to break the circuit connections the 15 left-hand push-button is depressed and the cycle of operation just described is reversed. Due to the provision of the spaced or double cams the parts are balanced thus eliminating the strain upon the same. Further, the 20 means for limiting the movement of the racks, the ball holder and the cams eliminates undue strain upon the parts. By provision of the rack and pinion mechanism the depression of one push button always acts 25 positively to raise the other push button, so that the switch mechanism is always in a 30 position to be operated.

While I have illustrated and described one specific form which my invention may 35 assume in practice, it is to be understood that certain features thereof are susceptible to modification without departing from the spirit of the invention or the scope of the appended claims.

40 What I claim as new and desire to secure by Letters Patent of the United States is:—

1. In an electric switch, in combination, a spindle, a plurality of spaced cams fixed thereon, a resilient member confined between 45 said cams for moving the same, operating means for said member, and a movable contact associated with said cams.

2. In an electric switch, in combination, an operating rack, a pinion meshing therewith, a cam mounted co-axially with said pinion, a resilient device carried by said pinion and bearing against said cam to impart an accelerated movement to the latter upon operation of said pinion, and a contact 55 member movable with said cam.

3. In an electric switch, in combination,

a pivoted member having a cam surface disposed in the direction of its axis, operating means therefor including a pinion and a spring-pressed device carried thereby and biased against said cam, and contacts movable with said member.

4. In an electric switch, in combination, two relatively movable and co-axially pivoted members having engaging parts, one 60 part being yieldable and resiliently bearing against the other to alternately impede and impel movement of one member in one direction during movement of the other member in the other direction, operating means for 65 said last mentioned member, and a movable contact associated with the other member.

5. In an electric flush switch, in combination, a pair of rectilinearly movable racks having push button extremities, a pinion 70 meshing with said racks and interlocking the same to move in opposite directions, a pair of co-axially pivoted members disposed on opposite sides of said pinion and having convex cams projecting toward the same, 75 and resilient means carried by said pinion and confined between said cams to receive and store energy during initial movement of said pinion and to thereafter expend such energy in imparting accelerated movement 80 to said pivoted members in a direction opposite to the movement of said pinion.

6. In an electric switch, a pinion, a plurality of push button operated racks meshed therewith, a spindle on which said pinion 90 is loosely mounted, spaced cams fixed to said spindle, and resilient operative connections between said cams and said pinion.

7. In an electric switch, a contact operating mechanism comprising a spindle, a plurality of spaced cam members fixed to said spindle and having peaked active surfaces, a contact member movable with said cam members, a pinion loosely mounted on said spindle between said cam members, and resilient operative connections between said pinion and said cam members for giving the latter a quick snap action upon movement of said pinion.

In witness whereof, I have hereunto subscribed my name in the presence of two witnesses.

CHARLES J. KLEIN.
